Attorney

UNITED STATES PATENT OFFICE.

IRVIN RADER, OF READING, PENNSYLVANIA, ASSIGNOR TO NOLDE & HORST COMPANY, OF READING, PENNSYLVANIA, A CORPORATION OF PENNSYLVANIA.

HOSIERY-HOLDER FOR EMBROIDERING-MACHINES.

1,222,670.

Specification of Letters Patent.

Patented Apr. 17, 1917.

Application filed September 28, 1915. Serial No. 52,977.

To all whom it may concern:

Be it known that I, IRVIN RADER, a citizen of the United States, residing at Reading, in the county of Berks and State of Pennsylvania, have invented certain new and useful Improvements in Hosiery-Holders for Embroidering-Machines, of which the following is a specification.

My invention relates to fabric-holding devices employed in connection with embroidery machines; and it consists in an improved construction adapted more particularly for hosiery and having as its essential feature a rigid one-piece frame formed of a bent bar and carrying independently locked clamping bars arranged wholly within the plane of the frame, as fully described in connection with the accompanying drawing and specifically pointed out in the claim.

The drawing illustrates a hosiery holder embodying the invention and showing different positions of the clamping bars with their pivoting and locking connections.

The main object of the invention is to provide a holder device of simple and satisfactory construction and operation, having all its portions arranged in the same plane so as to permit of easily introducing and controlling the previously clamped fabric for the embroidery operation.

The horizontal frame *a* is formed in a single piece, from a rod or bar of metal of uniform cross-section having its ends rigidly united; this endless bar being bent to ring-like form but having parallel top and bottom portions *2*, *3*, connected as shown by side portions *4*, *4*, which are generally curved as indicated so as to form corner portions *5*, *6*, *6*. Adjacent each of these corners, the frame is provided respectively with a fixed outwardly extending pivot ear *7* and with a laterally extending pivot aperture *8*; the latter extending through a portion of the frame bar which is provided with a link-engaging slot *9*.

Similar clamping bars, *10*, *11*, *12*, *12* are provided for the top and bottom portions *2*, *3*, and side portions *4*, *4* of the frame; one end of each of said clamping bars, as shown, being slotted and apertured to pivotally engage a fixed pivot ear *7* of the frame, and

the other end being slotted to engage a link *15* which is pivoted in a link-engaging slot *9* of the same portion of the frame.

55

Each of these bars *10*, *11*, *12*, *12* conforms with the end or side portion of the frame to which it is connected and with which it cooperates in clamping the interposed fabric; and each is adapted to be independently 60 pressed into clamping contact by a locking cam lever *16* which is pivotally carried by the free end of a link *15*, as shown. The contacting faces of the frame and clamping bars provide a recessed engagement adapted 65 to securely grip the fabric; and all of the clamping bars, together with their pivoting and locking connections, lie wholly within the plane of the frame, so as to provide a rigid device of minimum and uniform thickness 70 throughout, which permits of easily placing and manipulating the previously clamped fabric with relation to the embroidery mechanism in connection with which it is to be used. The straight top portion *2* of 75 the frame as shown, is of proper length to receive and clamp the wider portion of a full-fashioned hosiery fabric, the narrower portion of which is then clamped to the shorter bottom portion *3* and the edges to 80 the side portions *4*, *4*, of the holder; and the properly stretched fabric after being thus secured, is readily placed beneath or withdrawn from the embroidery needles, and freely controlled during the embroidery 85 operation so as to accurately produce desired effects.

What I claim is:

A hosiery-holder for embroidery machines consisting of a rigid open frame 90 formed of an endless bar of uniform cross-section bent to form parallel end portions and integral corner portions, outwardly extending pivot ears rigidly fixed to said bar adjacent the respective corner portions, separate clamping bars for each end and side portion of said frame connected to the respective pivot-ears, and separate locking means for the free ends of said bars each comprising a swinging-link connection to 100 the frame and a cam lever.

In testimony whereof I affix my signature.

IRVIN RADER.
